UNITED STATES PATENT OFFICE.

ELEANOR BERGSTROM, OF NEW YORK, N. Y.

TOILET ARTICLE.

Application filed July 1, 1924 Serial No. 723,566.

The present invention consists of a toilet article and is designed as an improvement on my Patent Number 1,492,196, issued April 29, 1924.

Objects of the invention are to provide a toilet article in the nature of a shield to prevent cosmetics, such as powder, massage cream, or the like, from coming in contact with the clothes of the user while being applied to the face or neck, the shield being foldable for convenience in carrying the same and likewise to occupy a minimum amount of space when not in use; to provide a shield of this character which may be supported by the hand or, if desired, which may be supported on the neck, by suitable means, to permit use of both hands while the shield is in place; and to provide a lightweight shield of simple construction and effective in use for the purpose for which it is designed and intended.

Other objects of the invention will be apparent from the following description taken in connection with the accompanying drawings of the present preferred forms of the invention wherein:

Fig. 1 is an elevational view of a toilet article or shield constructed in accordance with this invention illustrating its application;

Fig. 2 is a similar view showing the cover of the shield removed, dotted lines being employed to illustrate the frame in collapsed position.

Fig. 3 is a top plan view of the shield with the cover removed; and

Fig. 4 is an elevational view of a modified form of shield, the cover being shown fragmentarily thereon.

In my issued patent referred to supra a rigid frame is shown upon which a cover is mounted. In the present instance I prefer to employ a collapsible frame consisting of a pair of curved side rods 5 one end of each of which is hingedly connected to a handle 6. The opposite end of one of said rods 5 is hingedly connected with one end of an upper and neck engaging rod 7, the opposite end of the latter being provided with an opening 8 through which the outer end of the opposite side rod 5 is engaged. It will be noted, upon reference to Figs. 2 and 3 of the drawings that the outer end of the side rod 5 which is arranged through the opening 8 is reduced and curved to provide a bill 9 which is designed to grip the top rod 7 and pre-

vent casual disengagement of the latter and the side rod with which it is detachably engaged. Said top rod 7 is provided with a substantially semicircular depression 10 midway its ends which is designed to receive the neck of the user and conforms to the shape of the neck so as to snugly embrace the latter. The portions of said rod 7 on the opposite sides of the recess 10 provide wings 11 which are adapted to overhang the shoulders of the user in a manner more fully hereinafter described.

It is preferable to make the frame of the shield out of an inherently resilient material such as steel wire so that when the frame is in an open position the parts thereof are under a slight tension to prevent casual collapse of the frame. The frame is adapted to receive a covering such as designated at 12 and shown in Fig. 1 of the drawings. The covering may be made from any suitable fabric and in view of the inherent resilience of the frame will be normally held stretched or taut so as to provide a relatively stiff body which, however, may be folded with the frame or may be removed with facility when the frame is collapsed if desired. The covering may be ornamented or may be equipped with advertising matter if desired.

In using this device the shield will be placed in substantially the position shown in Fig. 1 with the concave or recess portion 10 of the frame impinging the neck, in which position the wings 11 overhang the shoulders while the handle 6 of the shield is held in the hand of the user so as to permit the shield to be disposed at a right angle to the face of the user. Surplus powder or the like falling from the face of the user will be intercepted by the shield so as to prevent the powder, or other cosmetic applied to the face, from coming in contact with the apparel of the user. The frame can be collapsed by disengaging the bill 9 from the recess 8 of the top rod of the frame thereby permitting said top rod to be folded between the two side rods into the position shown by dotted lines in Fig. 2.

The form of invention shown in Fig. 4 differs from the structure shown in Figs. 1 to 3 inclusive in that the handle 6 is eliminated and the sides 5' pivotally connected together as indicated at 13. Instead of supporting the shield by the handle I use instead a neck encircling strap 6' the opposite ends of which are detachably engaged, by

stud and socket or similar fastening means, as indicated at 14, to the frame covering 12'. The strap 6' is preferably elastic and is adapted to snugly embrace the neck so as to hold the body of the shield at right angles beneath the chin thereby permitting freedom of both hands for use in applying cosmetics such as powder, massage preparations or the like. Any particles gravitating from the face will be intercepted by the body in an apparent manner.

It is manifest that in a device of this character numerous changes may be made to adapt the device for different uses or to satisfy the caprice of a manufacturer. It is to

be understood that the present application embodies simply preferred forms of the present invention and I am aware that numerous improvements may be made within the scope of the claim hereto appended.

What is claimed is:

A powder shield of the character described including a frame provided with top and side rods hingedly connected together, said rods being foldable to collapse the frame, and a covering detachably mounted on said frame.

In testimony whereof I affix my name.

ELEANOR BERGSTROM.
